UNITED STATES PATENT OFFICE.

WILLIAM B. DUNNING, OF GENEVA, NEW YORK.

MAGAZINE STEAM-BOILER.

SPECIFICATION forming part of Letters Patent No. 349,699, dated September 28, 1886.

Application filed January 23, 1886. Serial No. 139,849. (No model.)

To all whom it may concern:

Be it known that I, WILLIAM B. DUNNING, a citizen of the United States, residing in Geneva, in the county of Ontario and State of New York, have invented certain new and useful Improvements in Magazine Steam-Boilers, of which the following is a specification.

My invention relates to steam-boilers; and the invention consists in certain improvements of the magazine-boiler for which a patent was granted to me April 12, 1870, No. 101,718, which said improvement is hereinafter more fully described.

The drawing is a transverse vertical section of a boiler set ready for use with my improvement applied thereto. The boiler B, as shown, is made annular in form, with a fire-chamber, C, in its interior at or near the bottom, and which extends upward around the magazine M, which is suspended centrally from the top. At a point about two-thirds the height of the boiler there is an annular enlargement, E, of the fire-chamber C, from which a series of flues, *a*, extend downward through the annular water-space of the boiler B, through which flues the products of combustion are compelled to pass to the bottom, thence passing upward around the exterior of the boiler through an annular flue, *h*, and thence into the chimney L through an opening or pipe, O, as indicated by the arrows. The external flue, *h*, is usually formed by inclosing the boiler in brick-work, as shown, though a metallic jacket is sometimes substituted for the brick-work, more especially with the smaller-sized boilers, and when they are designed to be set in rooms where they are constantly in sight, simply for convenience or appearance.

Thus far I have described the boiler as I have heretofore made it, and when thus made it will be seen that there is no escape for the smoke or products of combustion, except down through the flues *a*, as above described. When starting a fire at the beginning of the season, or at any time after the fire has been extinguished for some considerable time, the chimney, and all the flues both inside and outside of the boiler, will of course be filled with cold air, which, being heavier than the flame and smoke created by the newly-kindled fire within the boiler, cannot be readily or immediately forced

out through the chimney, and as the flame, smoke, and gases within cannot enter and pass off through the chimney, and are constantly being increased in volume, the result is, that they are forced out into the room, sometimes with considerable force, owing to the pressure of the gases within the fire-chamber. To remedy this difficulty I provide the boiler with a flue or tube, J, as shown in the drawing, this flue J extending from the enlarged fire-chamber E directly upward through the steam-dome D and out through the top, the joints being rendered steam-tight where it passes through the dome or chamber D, both above and below. The upper end of this flue J is then connected by an elbow and pipe with the smoke-flue or chimney L, as shown in the drawing. I arrange a valve or damper, *e*, in the pipe, preferably as near the boiler as is convenient, by which the draft through the flue J can be stopped, when desired.

When starting a fire, the damper *e* is opened, thus allowing the hot gases and smoke to pass directly upward through the flue J, and from thence into the chimney L, from which they soon force the cold air and establish a strong upward current therein. As soon as the boiler becomes warmed and a good current is established in the chimney, the damper *e* is closed, when the products of combustion immediately take the route down through the lower flues, *a*, and thence up around the boiler and through the passage *o* into the chimney L, this being their normal route when the boiler is in operation. By this improvement the difficulty previously mentioned is entirely overcome, and a fire can be started at any time without the annoyance of gas or smoke entering the room from the fire-chamber. The same result may be accomplished by making an opening, *r*, through the side of the boiler, and providing it with a damper, *e'*, as shown at the right-hand side of the figure. If this plan be used, the opening *r* should be made at the back side of the boiler, or as near the smoke-flue O as may be convenient, and above the brick diaphragm *m*, as shown, so that the smoke and gases may have the shortest and most direct route possible to the chimney. The damper *e'* in such case may be hinged, so as to be turned up when open, as shown in the drawing, in which case it will be held shut by grav-

ity; or it may be arranged to slide, or be pivoted so as to turn the same as the damper *e* in the pipe *J*, the form or arrangement of the damper being merely a matter of choice or convenience 5 for the manufacturer. It will of course be understood that, whichever form be used, a rod will be connected to it and made to extend out through the brick-work or casing, by which it can be opened and closed at will. Either form of 10 direct draft may be used at will; but I prefer the vertical flue *J*, for the reason that it is frequently necessary to so locate the boiler in buildings already erected that its back side will not be next to the chimney, the smoke-pipe 15 sometimes having to be carried across the room to a chimney at the opposite side, the exit-opening *O* having to be located at one or the other side, or possibly at the front side, of boiler, and in such cases, by using the upright flue 20 or tube *J*, the smoke-pipe connected thereto can be turned or carried in any desired direction to suit the circumstances of the case. This direct draft is also useful to assist in starting up the fire whenever it has become low and it 25 is desired to get up steam quickly. So, too, it may be used to a greater or less extent in connection with the indirect draft by properly adjusting the damper in those cases where the draft of the chimney is not as good or strong 30 as desired, and which is not unfrequently the case in private dwellings built without reference to the use of a steam-heater, and into which it is now a common practice to introduce this style of boiler.

35 In an application filed by me January 7, 1886, Serial No. 187,702, I have shown and described a boiler which has an annular flue instead of

the series of descending flues *a* shown in this, and in which the enlargement of the fire-chamber extends all the way to the top of the boiler, 40 there being no dome or steam-chamber *D* over the fire-chamber, as in this case; and it is obvious that this improvement in either of its forms may be applied to that form of boiler the same as to this, and I propose to so apply and 45 use it. In that case, if the vertical flue *J* be used, it would simply start at the top or covering plate, and would not pass through the steam-chamber, while if the lateral flue *a* were used it would pass through the outer water 50 chamber or shell at any desired point at or near its upper end.

I am aware that both stoves and boilers have been made with a direct and an indirect draft, and also that steam-boilers have been constructed with direct and indirect drafts in various ways, and that boilers have been patented showing a smoke bonnet or chamber over the steam-space or top of the boiler with a direct smoke-flue leading therefrom, and I 60 do not claim any of these; but

What I do claim is—

In combination with the boiler *B*, the central magazine, *M*, the surrounding fire-chamber *C*, having the annular enlargement *E*, with the 65 descending flues *a*, for the indirect draft, and the upright flue *J*, or its equivalent outlet from the enlargement *E*, for a direct draft, and a damper for closing the same, substantially as shown and described.

WM. B. DUNNING.
